[57] CLAIM

The ornamental design of a pocket watch, as shown and described.

DESCRIPTION

FIG. 1 is a front elevational view of a pocket watch showing my new design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a front elevational view of another embodiment of my new design of FIGS. 1-6;

FIG. 8 is a right side elevational view thereof, the left side view being a mirror image thereof;

FIG. 9 is a rear elevational view thereof; and

FIG. 10 is a bottom plan view thereof, the top plan being substantially a mirror image thereof.

A top plan view of the watch shown in FIG. 7 would correspond to that shown in FIG. 8.
